[57] CLAIM

The ornamental design for a bracket for wall lamps and similar articles, substantially as shown and described.

DESCRIPTION

FIG. 1 is a side elevational view of a bracket for a wall lamp or a similar article showing my new design;
 FIG. 2 is a top plan view thereof;
 FIG. 3 is a bottom plan view thereof;
 FIG. 4 is a rear elevation view thereof;
 FIG. 5 is a top front perspective view thereof;
 FIG. 6 is a front elevational view thereof;
 FIG. 7 is a side elevational view of a second embodiment of my new design;
 FIG. 8 is top plan view of the embodiment shown in FIG. 7;
 FIG. 9 is a front elevational view of the second embodiment shown in FIG. 7.
